(57) **CLAIM**

The ornamental design for a garlic smasher and keeper, as shown and described.

DESCRIPTION

FIG. 1 is a perspective view of a garlic smasher and keeper showing my new design;

FIG. 2 is a front view of the garlic smasher and keeper of FIG. 1, the rear view, the right side view and the left side view being mirror images thereof;

FIG. 3 is a top plan view of FIG. 1;

FIG. 4 is a bottom plan view of FIG. 1;

FIG. 5 is a perspective view showing the garlic smasher and keeper of FIG. 1 with the garlic smasher removed;

FIG. 6 is a front view of FIG. 5, the rear view, the right side view and the left side view being mirror images thereof;

FIG. 7 is a top plan view of FIG. 5;

FIG. 8 is a bottom plan view of FIG. 5;

FIG. 9 is a perspective view showing the garlic smasher of the garlic smasher and keeper of FIG. 1;

FIG. 10 is a front view of FIG. 9, the rear view, the right side view and the left side view being mirror images thereof;

FIG. 11 is a top plan view of FIG. 9; and,

FIG. 12 is a bottom plan view of FIG. 9.
